UNITED STATES PATENT OFFICE.

WILLIAM R. BLANCHARD, OF BREMEN, OHIO.

POSITION INDICATING AND COMMUNICATING DEVICE FOR SUBMERGED CRAFT.

Application filed February 15, 1928. Serial No. 254,509.

This invention relates to a device for indicating the position of submerged or sunken craft and for communication therewith and more specifically to a float associated with the deck of the craft which is designed to be released from within the craft and which contains means for communicating with said craft.

The dangers and horrors of sea-going craft are too well known to require discussion and the various disasters occurring from time to time are shocking and unnecessary. One of the difficulties lies in locating a sunken craft and another lies in communicating with the same. The old method of grappling is both slow and costly both in money and in lives. Communication is poor and requires undue or impossible effort on the part of those within the submerged craft at just those times when they must conserve all possible strength and reduce the consumption of oxygen to a minimum. The present invention will overcome all these difficulties and provide speedy and certain means of indicating the position of the craft and communication therewith.

Among the objects and advantages of the present invention are: the provision of a float which may be released from within a submerged craft; the provision of a float which when released will enable searchers to locate and communicate with the submerged craft; the provision of separable means operable from one side of a deck construction to release a device on the other side and which is at all times absolutely waterproof and watertight; and the provision of an efficient device admirably adapted to perform the functions for which it is intended.

For the attainment of the foregoing objects and such other objects as may herein-after appear or be pointed out, I have illustrated the preferred embodiment of my invention in the accompanying drawings wherein:

Figure 1 is an elevational view of a submarine on the surface equipped with my invention, the relative size of the invention being exaggerated for clarity;

Figure 2 is a view of a submarine resting on the bottom and showing the invention released and floating in the position it would take in actual use;

Figure 3 is a longitudinal vertical section through the invention and the subjacent deck

construction, the scale being magnified for clarity;

Figure 4 is a fragmentary view partially in elevation and partially in section showing the position of certain parts just after release thereof;

Figure 5 is a plan view of the float; and Figure 6 is an elevation of the float looking from the left of Figure 5.

Similar numerals refer to similar parts throughout the several views.

In the drawings, I have illustrated my invention in connection with a submarine since it is that type of craft to which I have directed my invention particularly, although I can apply it to any craft or ship having men in a watertight compartment below deck. Also I may provide my invention at any desirable point between the bow and stern and I may have as many units as required by the ship.

The submarine 1 is provided with a deck 2 in the usual manner. The float 3 may rest directly upon the deck 2, as shown; but if desired the deck may be recessed to receive the float in a manner to have the top thereof flush with the deck. The guard member 4 is pivoted to the deck at 5. This guard member, as shown, partially overlies the float and maintains it in position against any tendency to rise or be displaced in the normal operation of the submarine. This guard member may be positively actuated from within the submarine by any suitable means (not shown).

The float 3 may consist of any floatable construction and may be the hollow steel cylinders shown. The float is provided with a hollow dome 6 lying between the cylinders of the float and connected thereto as by steel straps 7. At the top of the dome is the ringbolt 7 securely fastened by a nut, the purpose of which will be apparent hereinafter. As is clear from Figure 3, the dome is provided with pockets or recesses 8 and 9 containing cages or bridles 10 and 11. The ring at the top of the cage 10 is connected to the eyebolt 7 by means of a short length of heavy rope 12. The manilla hawser or rope 13 is long and heavy and is tied at one end to the ringbolt 7 and at the other end to the deck as by a ring 14. The rope 13 is coiled about the cage 10 in a manner permitting ready and free uncoiling at all times when tension is put on the 110

end of the rope. The pieces 15 and 16 are the halves of the separable releasing means or threaded irregularly divided bolt which forms an important part of my invention. The piece 15 is swivelly mounted in the bottom of the cage 10 in a manner permitting free rotatory movement but preventing relative vertical movement between the elements 10 and 15. The piece 16 is complementary to and interfitting with the piece 15 as shown but the pieces merely abut each other and are not secured in any way. If desired, the deck may be thickened or reinforced by the plate 17 which may both strengthen the deck and add threads for the better operation of the releasing means since the deck and the plate are both provided with registering threaded holes. Numeral 18 indicates an internally threaded member which overlaps the abutting ends of the pieces 15 and 16 and keeps them in proper relative position as well as preventing the piece 16 from falling off. This member may be a suitable union or collar as shown or may be a boss or extension of the plate 17 or deck 16. In practice it may be necessary to provide packing for the screw so that water can not enter. Piece 16 has the hand wheel or handle 19 at its lower end which is used to turn up the screw at the proper time.

The cage 11 is firmly fixed to the deck, as shown clearly, in contradistinction to cage 10 which is not so fixed. Cage 11 carries coiled thereabout, similarly to rope 13 on cage 10, the hollow flexible cable 20 which contains wires 21 and 22 and any other desired wires or connections. The top end of this cable 20 is fixed in the top of the pocket 9 so the wires 21 and 22 emerge therefrom within the dome of the float, as shown, the wire 21 leading to the ball antenna 23 and the wire 22 leading to the telephone 24. The ball antenna 23 and the telephone 24 are suitably located within the dome 6. The dome is further provided with a watertight door 25 and aprons 26 and 27. The door 25 permits access to the interior of the dome and the instruments located therein. Aprons 26 and 27 are depending flanges which extend to the deck and prevent water getting under the float to any appreciable extent and prevent waves etc. from having any tendency to displace the apparatus.

The lower end of cable 20 passes through the deck construction using known watertight connections and the wires 21 and 22 emerge within the interior of the craft or compartment thereof, 21 leading to the radio and 22 to the inside telephone as indicated on Figure 3.

The operation of the device is thought to be clear from the foregoing but a brief summary will be included at this point. Let us assume that the submarine is disabled and

resting under water as in Figure 2. Guard 4 is now first moved out of engagement with the float and assumes a position such as that in Figure 2. The manner of operating the guard is suitably provided but is not shown as it does not constitute part of the present invention. When the guard is out of the way, the buoyancy of the float 3 will tend to make it rise and it will rise, but only to the amount permitted by the length of the rope 12 as is evident. This slight rise, however, allows space for the rise of the cage 10 when next the handle 19 is turned to turn up the screw pieces 15 and 16. This is continued until the handle abuts the collar or boss 18. Immediately the piece 15 is wholly above the deck, the cage is freed and so, consequently, is the float, whereupon the whole rapidly ascends to the surface, the rope 13 and the cable 20 freely uncoiling to permit the same. The final position of the parts is as shown in Figure 2 where rope 13 and cable 20 are fully uncoiled and freely connect the float and the submarine. The cage 11 is left behind, as is understood, on the deck, and cage 10 hangs from the float by rope 12, piece 15 remaining in the cage.

Through the ball antenna any suitable radio communication is possible such as sending out "S O S" or messages of any kind. The rescue ships can thus readily locate the submarine by locating the float. The telephone permits unlimited communication between the rescuers and the entrapped. If desired, the cable 20 can be of appropriate size and material to receive air and food so that either or both can be supplied to the entrapped men. The dome construction prevents damage to the communicating instruments by the elements while the float is released, and the dome and aprons prevent damage to or displacement of the communicating instruments and cages, ropes, and cables while the float is on the deck of the submarine.

The above can be readily carried out in a very short space of time and the advantages will be both numerous and evident from the foregoing.

The whole can be cheaply and easily made and assembled and is rapid and efficient in operation. Any number of the devices may be used, for example, one for each compartment of the submarine, if desired.

All the above matters are intended to be more illustrative than limitative so that I do not limit myself thereto except as contained in the subjoined claims.

Having thus described my invention and illustrated its use, what I claim as new and desire to secure by Letters Patent of the United States is:

1. In a device of the character described, a deck, a float on the deck, a guard for preventing displacement of the float, a cage

connected to the float between the same and the deck, a separable bolt means passing through the deck, one end of which is swivelly connected with the cage, and means for 5 releasing float, cage, and the upper half of the bolt from the other side of the deck.

2. In a device of the character described, a float, means for communication within the float, and pockets in the underside of the 10 float for the housing of cages carrying means of connection and communication with the ship associated therewith.

3. In a device of the character described, a deck construction, a float resting upon said deck, a guard member partially overlying 15 said float, means for communication within said float, pockets in the underside of said float, cages housed by said pockets and means associated with each cage passing through the deck construction in a watertight manner.

In testimony whereof I hereunto set my hand this 11th day of February, 1928.

WILLIAM R. BLANCHARD.
